UNITED STATES PATENT OFFICE

161,100

X-RAY APPARATUS

Edwin R. Goldfield and Robert J. Stava, University Heights, Ohio, assignors to Picker X-Ray Corporation, Waite Manufacturing Division, Inc., Cleveland, Ohio, a corporation of Ohio

Application January 24, 1950, Serial No. 7,435

Term of patent 14 years

(Cl. D61—1)

To all whom it may concern:

Be it known that we, Edwin R. Goldfield and Robert J. Stava, citizens of the United States, both residing at University Heights, county of Cuyahoga, and State of Ohio, have invented a new, original, and ornamental Design for X-Ray Apparatus, of which the following is a specification, reference being had to the accompanying drawings, forming a part hereof.

Fig. 1 is a perspective view showing the front and one end of the X-ray apparatus embodying our invention and Fig. 2 is a perspective view showing the rear and opposite end of the same.

We claim:

The ornamental design for X-ray apparatus, as shown.

EDWIN R. GOLDFIELD.
ROBERT J. STAVA.
